UNITED STATES PATENT OFFICE.

JAMES F. HINES, OF LAKWOOD, OHIO.

FLASK.

Application filed April 10, 1925. Serial No. 22,063.

My invention relates to flasks and the principal object of my invention is to provide new and improved means for alining flask sections. In the drawings accompanying this specification and forming a part thereof I have shown, for purposes of illustration, one form which my invention may assume. In these drawings:

Figure 1 is a plan view of this illustrative embodiment of my invention,

Figure 2 is a side elevation of this illustrative embodiment of my invention,

Figure 3 is an end elevation of this illustrative embodiment of my invention,

Figure 4 is a section on the line 4—4 of Figure 1, while

Figure 5 illustrates a method of forming the follower.

The flask herein shown comprises a drag section 11 and a cooperating cope section 12, and a plurality of means for alining these two sections each of which comprises a bracket 13 formed integral with the drag section 11 and a cooperating bracket 14 formed integral with the cope section 12. Each of these drag section brackets 13 is provided with a pair of apertures 15 through which extend the reduced extensions 16 of a pair of cylindrical pins 17 which are firmly held to the bracket 13 by means of nuts 18 coacting with the cooperatively screw-threaded surfaces of the extensions 18, while each of the cope section brackets 14 carries a follower 19 secured to the bracket 14 by means of bolts 20 and formed to embrace each of the pins 17 throughout approximately half the circumference of each pin.

Because of the construction of these followers 19, and the extent to which they embrace the pins 17, I find it convenient to manufacture the followers by forming completely machined the double follower 21 shown in Figure 5 and to then split this double follower along the line through the center of the two apertures 22.

It will be apparent from the above description that I have provided means for alining flask sections unusually rigid and accurate, effective to prevent tilting of the cope as it is being withdrawn from the drag, and unusually inexpensive to manufacture and apply. It will also be apparent that I may use the same means for alining a pattern plate with either or both of the flask sections, alinement of the pattern plate with

the cope section alone being accomplished by providing on the pattern plate pins 17 to cooperate with the existing follower 19 on the cope, and alinement of the pattern plate 60 with the drag alone, or with both the drag and the cope, being accomplished by providing on the pattern plate followers 19 to cooperate with the existing pins 17.

It will also be apparent to those skilled in the art that the embodiment of my invention herein shown and described embraces advantages other than those specifically pointed out or suggested herein and also that the particular embodiment of my 70 invention herein shown may be variously changed and modified without departing from the spirit of my invention or sacrificing the advantages thereof. It will therefore be understood that this disclosure is illustrative only and that my invention is not limited thereto.

I claim:

1. A flask comprising two sections to be alined, and a plurality of means for alining 80 said sections each comprising a pair of spaced pins secured to one of said sections, and follower means secured to the other of said sections and formed to at least partially embrace each of said pins.

2. A flask comprising two sections to be alined, and a plurality of means for alining said sections each comprising a pair of pins secured to one of said sections and spaced from each other in the direction of extent 90 of the adjacent section wall, and follower means secured to the other of said sections and formed to at least partially embrace each of said pins.

3. A flask comprising two sections to be 95 alined, and a plurality of means for alining said sections each comprising a pair of spaced pins secured to one of said sections, and follower means secured to the other of said sections, engaging the same side of 100 both cooperating pins, and formed to at least partially embrace each of said pins.

4. A flask comprising two sections to be alined, and a plurality of means for alining said sections each comprising a pair of 105 spaced pins secured to one of said sections, and follower means secured to the other of said sections, engaging said pins in a direction generally normal to the adjacent section wall, and formed to at least partially 110 embrace each of said pins.

5. A flask comprising two sections to be

alined, and a plurality of means for alining said sections each comprising a pair of pins secured to one of said sections and spaced from each other in the direction of extent 5 of the adjacent section wall, and follower means secured to the other of said sections, engaging the same side of both cooperating pins and in a direction generally normal to the adjacent section wall, and formed to at 10 least partially embrace each of said pins.

6. A flask comprising two sections to be alined, and a plurality of means for alining said sections each comprising a pair of spaced cylindrical pins secured to one of 15 said sections, and follower means secured to the other of said sections and formed to at least partially embrace each of said pins.

7. A flask comprising two sections to be

alined, and a plurality of means for alining said sections each comprising a pair of 20 spaced pins secured to one of said sections, and a one-piece follower secured to the other of said sections and formed to at least partially embrace each of said pins.

8. A flask comprising two sections to be 25 alined, and a plurality of means for aligning said sections each comprising a pair of spaced cylindrical pins secured to one of said sections, and a one-piece follower secured to the other of said sections and 30 formed to at least partially embrace each of said pins.

In testimony whereof I hereunto affix my signature.

JAMES F. HINES.
